(57) **CLAIM**

The ornamental design for a dragon tail shaped guitar, as shown and described.

DESCRIPTION

FIG. 1 is a front elevational view of a dragon tail shaped guitar showing my new design;

FIG. 2 is a right side elevational view thereof;

FIG. 3 is a front elevational view thereof, shown in use; and,

FIG. 4 is a rear elevational view of FIG. 1.

The broken lines shown in the drawings are for illustrative purposes only and form no part of the claimed design.
